FOOD CAN

Jose Anacleto dos Santos Dias, Palmela, Portugal, assignor of fifty percent to Instituto Portugues de Conservas de Peixe, Lisbon, Portugal, a Portuguese company

Filed Apr. 16, 1959, Ser. No. 55,539

Term of patent 7 years

(Cl. D58—17)

FIG.1

FIG.2

FIG.3

FIG.4

Fig. 1 is a perspective view of a food can, showing my new design;

Fig. 2 is a top plan view of the cover portion thereof;
Fig. 3 is a cross sectional view taken on line 3—3 of Fig. 2.

Fig. 4 is a cross sectional view taken on line 4—4 of Fig. 2.

The characteristic features of my design for the can disclosed reside in the cover portions having the configurations shown.

I claim:

The ornamental design for a food can, substantially as shown and described.
